(57) **CLAIM**

The ornamental design for an exit device, as shown and described.

DESCRIPTION

FIG. 1 is a top, front, left side perspective view of an embodiment of an exit device;

FIG. 2 is a top, front, right side perspective view of FIG. 1;

FIG. 3 is a front elevation view of FIG. 1;

FIG. 4 is a rear elevation view of FIG. 1;

FIG. 5 is a left side elevation view of FIG. 1;

FIG. 6 is a right side elevation view of FIG. 1;

FIG. 7 is a top plan view of FIG. 1;

FIG. 8 is a bottom plan view of FIG. 1;

FIG. 9 is a top, front, left side perspective view of another embodiment of an exit device;

FIG. 10 is a top, front, right side perspective view of FIG. 9;

FIG. 11 is a front elevation view of FIG. 9;

FIG. 12 is a rear elevation view of FIG. 9;

FIG. 13 is a left side elevation view of FIG. 9;

FIG. 14 is a right side elevation view of FIG. 9;

FIG. 15 is a top plan view of FIG. 9; and,

FIG. 16 is a bottom plan view of FIG. 9.

The dash-dash broken lines show portions of the exit device that form no part of the claimed design. The dot-dash broken lines represent boundaries of the claimed design and form no part of the claimed design. Any broken line illustration of environmental structure in the drawing is not part of the design sought to be patented.

1 Claim, 16 Drawing Sheets
